UNITED STATES PATENT OFFICE

RONALD A. McCANN, OF SWISSVALE, PENNSYLVANIA, ASSIGNOR TO THE UNION SWITCH & SIGNAL COMPANY, OF SWISSVALE, PENNSYLVANIA, A CORPORATION OF PENNSYLVANIA

RAILWAY TRAFFIC CONTROLLING APPARATUS

Application filed October 2, 1929. Serial No. 396,813.

My invention relates to railway traffic controlling apparatus, and particularly to apparatus of the type involving traffic governing mechanism controlled by energy received from the track rails. More particularly, my present invention relates to means for supplying such energy to the track rails.

I will describe five forms of railway traffic controlling apparatus embodying my invention, and will then point out the novel features thereof in claims.

In the accompanying drawings, Fig. 1 is a diagrammatic view showing one form of apparatus embodying my invention. Figs. 2, 15 3, 4 and 5 are views showing modifications of the apparatus shown in Fig. 1, and also embodying my invention.

Similar reference characters refer to similar parts in each of the several views.

20 Referring first to Fig. 1, reference characters 1 and 1^a designate the track rails of a stretch of railway track over which traffic moves in the direction indicated by the arrow. These rails are divided by insulated joints 2 to form a plurality of successive sections *d*—*e*, *e*—*f*, etc. Each track section is provided with a track circuit including a track battery 3 connected in series with secondary winding 4 of a transformer *t* across 25 the rails adjacent one end of the section, and a track relay designated by the reference character *R* with a distinguishing exponent and connected across the rails adjacent the opposite end of the section.

30 Current supplied by winding 4 each transformer *t* is controlled by an alternator designated, in general, by the reference character *A*; and by coders each of which is designated, in general, by the reference character *D* with a distinguishing exponent. As here shown, alternator *A* is of the vibrating reed type, comprising an elastic member 15 which is caused to vibrate between terminals 17 and 18 by a control winding 19. In the de-energized condition of alternator *A*, as shown in the drawings, member 15 does not connect with either terminal 17 or 18 but does connect with a terminal 16. When energy is supplied to alternator *A*, winding 19 will attract member 15 causing it to connect with terminal 18 and

to move away from terminal 16, causing winding 19 to be de-energized. Upon the de-energization of winding 19, the resilience of member 15 will cause it to move away from terminal 18 and to connect with terminal 17 as well as with terminal 16. The circuit for winding 19 being then again completed through terminal 16, winding 19 will again attract member 15 causing the cycle of operation just described to be repeated. Winding 19 will thus be repeatedly energized and de-energized as long as energy is supplied to its control circuit. The frequency of such energization of winding 19 may be of any suitable value, as for example, 100 times per second.

55 Each coder *D*, as here shown, is of the pendulum type, comprising a contact 20, a contact 23, a control winding 24, and a pendulum 25 which biases contact members 20 and 23 to the position shown in the drawings when winding 24 is de-energized.

60 Relay *K* is a type which is so designed as to have a slow pick-up, and the purpose of this relay is to conserve the energy of battery *Q* by opening the circuits for alternator *A* and coders *D*¹ and *D*² if a train occupies section *d*—*e* for an abnormally long period of time such, for example, as when an engine 65 is taking water or when a train is standing at a station.

65 Relay *P* is controlled by a back contact of track relay *R*³. When relay *P* is energized, a battery *Q* supplies current to the control circuit for alternator *A*. When member 15 connects with terminal 18, battery *Q* also supplies current to the right hand portion of the primary winding 13 of a transformer *T*, and when member 15 connects with terminal 17, battery *Q* supplies current in the opposite direction to the left hand portion of the primary winding 13 of transformer *T*. Alternating current is therefore generated in the secondary winding 12 of transformer *T*. When contact 20 of coder *D*¹ or *D*² is closed while relay *R*⁴ is de-energized or is energized, respectively, a circuit is completed for secondary 12 of transformer *T* including the primary winding 9 of transformer *t*.

When relay P is energized, the operating circuit for coder D¹ or D² is also supplied with current by battery Q, causing winding 24 of coder D¹ or D², respectively, to attract its contact members 23 and 20. Contact 23 then opens the circuit for winding 24, and pendulum 25 then restores contacts 20 and 23 to the position shown in the drawings.

Coder D¹ or D² is controlled by relay P according as section e—f is occupied or is unoccupied, respectively. Coder D¹ is designed to operate at a given frequency, as for example, 80 times per minute, whereas coder D² is designed to operate at a different frequency, as for example, 180 times per minute, and hence the current generated in secondary winding 12 of transformer T is interrupted at one or the other frequency according as coder D¹ or D² is being operated.

Since the circuit for secondary winding 12 includes primary winding 9 of transformer t, the secondary winding 4 of which is connected in series with track battery 3 across the rails of section d—e, periodically interrupted alternating current generated in secondary winding 4 of transformer t is therefore supplied to the rails of section d—e, and may be used in any suitable manner for the control of train carried governing means or other railway traffic controlling apparatus.

As shown in the drawings, all parts are in their normal condition, that is, track sections d—e, and e—f are unoccupied; relays R³ and R⁴ are therefore energized; relay P is de-energized because relay R³ is energized; and alternator A, relay K, and coders D¹ and D² are de-energized.

I will now assume that a train enters section d—e, de-energizing relay R³ and thereby causing relay P to be energized by its circuit passing from battery Q, through the winding of relay P, and contact 29 of relay R³ back to battery Q. Relay P, upon becoming energized, completes, at its contact 27, the operating circuit for alternator A passing from battery Q, through contact 27, contact 15—16 of alternator A, winding 19 of alternator A, and contact 37 of relay K back to battery Q. Winding 19 therefore attracts member 15, causing current to be supplied to the right hand portion of primary winding 13 of transformer T by its circuit passing from battery Q, through contact 27 of relay P, contact 15—18 of alternator A, primary 13, terminal 14 of primary 13, and contact 37 of relay K back to battery Q. Winding 19 of alternator A, being now de-energized by its contact 15—16, releases member 15 which then springs back, connecting with terminal 17 and thereby closing a circuit for the left hand portion of primary 13 of transformer T, passing from battery Q, through contact 27 of relay P, contact 15—17 of alternator A, primary 13, terminal 14 of primary 13, and contact 37 of relay K back to battery Q.

Relay P, upon closing its contact 26, completes the operating circuit for coder D² passing from battery Q, through contact 26, contact 36^a of relay R⁴, contact 23 of coder D², winding 24 of coder D², and contact 37 of relay K back to battery Q. Coder D² is therefore caused to alternately close and open its contact 20, causing the circuit for primary winding 9 of transformer t to be periodically closed and interrupted. The circuit for primary winding 9 of transformer t passes from secondary winding 12 of transformer T, through contact 20 of coder D², contact 38^a of relay R⁴, and winding 9 of transformer t back to winding 12 of transformer T. Alternating current, interrupted with a frequency corresponding with that of the opening of contact 20 of coder D², is therefore generated in secondary 4 of transformer t.

If the train continues only a normal period of time within section d—e, relay K does not open its contact 37. If, however, the train remains for an excessive period of time within section d—e, relay K opens its contact 37 thereby breaking the operating circuits for alternator A, transformer T and coder D², and hence interrupting the supply of alternating current to section d—e. The control circuit for relay K passes from battery Q, through contact 28 of relay P, and the winding of relay K back to battery Q. When the train leaves section d—e, relay K at once closes its contact 37.

As soon as a second train enters section d—e, causing relay P to again become energized, the operation of alternator A is again resumed. Relay R⁴, being de-energized due to the presence of the first train in section e—f, causes coder D¹ to now be energized by its circuit passing from battery Q, through contact 26 of relay P, contact 36^b of relay R⁴, contact 23 of coder D¹, winding 24 of coder D¹, and contact 37 of relay K back to battery Q. A second circuit for primary winding 9 of transformer t is now periodically completed passing from secondary 12 of transformer T, through contact 20 of coder D¹, contact 38^b of relay R⁴, and winding 9 of transformer t back to winding 12 of transformer T. Section d—e is therefore now supplied with alternating current which is periodically interrupted with a frequency corresponding to that of coder D¹.

One feature of my invention is that it provides apparatus which requires only a small number of control contacts in the operating circuit for an alternator A and in the circuit which supplies current to primary 13 of a transformer T of apparatus of the type shown. This is accomplished by effecting most of the control in an auxiliary circuit which includes the primary winding of a transformer t and the secondary winding 12 of transformer T. Because of this feature,

which results in low total resistance of leads and control contacts, the voltage generated by battery Q can be of a lower value than would otherwise be necessary, and hence a 10 volt battery, such as is commonly used for other purposes in railway signaling apparatus, can be employed here also. Another feature of my invention is that it provides means for conserving the energy of battery Q.

Fig. 2 differs from Fig. 1 only in the control circuits for alternator A and transformer T, and in the omission of slow pick-up relay K. In Fig. 1, the current for operating alternator A as well as the current supplied to primary 13 of transformer T is carried through contact 27 of relay P, whereas in Fig. 2, the current for operating alternator A only is carried through contact 27, and the current supplied to transformer T is carried over the contacts of alternator A only. As here shown, the circuit for operating alternator A passes from battery Q, through contact 15-16 of alternator A, winding 19 of alternator A, and contact 27 of relay P back to battery Q. The circuits for primary winding 13 of transformer T, as also here shown, pass from battery Q, through contact 15-17 or 15-18 respectively of alternator A, and primary winding 13 back to battery Q.

A feature of the apparatus shown in Fig. 2 is, that, in addition to the means employed in Fig. 1 for reducing the number of control contacts in the operating circuits for alternator A and primary 13 of transformer T, the circuits for primary 13 of transformer T are here taken through contacts of alternator A only instead of through contact 27 of relay P as well as through contacts of alternator A.

The apparatus shown in each of the Figs. 1 and 2 is particularly applicable for railway traffic controlling systems comprising cab signals controlled by two "proceed" codes, but is not limited to such systems.

Referring now to Fig. 3, relay P and alternator A as well as the primary winding 13 of transformer T are controlled as in Fig. 1, except that relay K is here omitted, but the circuit for secondary winding 12 of transformer T is controlled by one of three coders D¹, D² and D³ according to traffic conditions. Relay M is controlled by relays R⁴ and R⁵ through its circuit passing from battery Q⁴, through contact 40 of relay R⁵, contact 41 of relay R⁴, and the winding of relay M back to battery Q⁴. Coder D¹ is operated when section e-f is occupied, coder D² is operated when section e-f is unoccupied while section f-g is occupied, and coder D³ is operated when both sections e-f and f-g are unoccupied. Coders D¹, D² and D³ may be designed to operate at frequencies of 80, 120, and 180 times per minute, respectively.

When a train enters section d-e, alternator A is operated and supplies current to

transformer T as described in connection with Fig. 1 except without the control by relay K. Relay P, upon becoming energized, also completes at its contact 26 the operating circuit for coder D³ passing from battery Q, through contact 26 of relay P, contact 39^a of relay M, contact 23 of coder D³, and winding 24 of coder D³ back to battery Q. Coder D³ then periodically closes and opens a circuit for winding 9 of transformer t passing from secondary 12 of transformer T, through contact 20 of coder D³, contact 42^a of relay M, and winding 9 of transformer t back to secondary 12 of transformer T.

When the train enters section e-f, de-energizing relay R⁴, coder D¹ is operated by its circuit passing from battery Q, through contact 26 of relay P, contact 39^b of relay M, contact 36^b of relay R⁴, contact 23 of coder D¹, and winding 24 of coder D¹ back to battery Q. Coder D¹ then continues to operate as long as the train occupies both sections d-e and e-f, or while one train occupies section e-f while a second train occupies section d-e. While the circuit for coder D¹ is connected with battery Q, a second circuit for primary winding 9 of transformer t is periodically closed and opened, passing from secondary 12 of transformer T, through contact 20 of coder D¹, contact 38^b of relay R⁴, contact 42^b of relay M, and winding 9 of transformer t back to secondary 12 of transformer T.

When the first train moves out of section e-f and occupies section f-g, the circuit for relay M is opened at contact 40 of relay R⁵ and hence relay M continues de-energized although relay R⁴ is now energized. If the second train still occupies section d-e and if section e-f is now unoccupied, coder D² will be operated by its circuit passing from battery Q, through contact 26 of relay P, contact 39^b of relay M, contact 36^a of relay R⁴, contact 23 of coder D², and winding 24 of coder D² back to battery Q. With coder D² operating, a third circuit for primary winding 9 of transformer t is periodically closed and opened, passing from secondary 12 of transformer T, through contact 20 of coder D², contact 38^a of relay R⁴, contact 42^b of relay M, and primary 9 of transformer t back to secondary 12 of transformer T.

When relay P is energized, it follows, therefore, that while section e-f is occupied, coder D¹ periodically closes and interrupts the circuit for primary 9 of transformer t with a frequency which is that of coder D¹; when section e-f is unoccupied while section f-g is occupied, coder D² periodically closes and opens the circuit for primary 9 of transformer t with a frequency which is that of the operation of coder D²; and that while both sections e-f and f-g are unoccupied,

coder D^3 periodically closes and opens the circuit for primary 9 of transformer t with a frequency which is that of the operation of coder D^3 .

My invention here embodies apparatus requiring only a small number of control contacts in the operating circuits for alternator A and primary 13 of transformer T as previously described in connection with Fig. 1, except that relay K is here omitted.

The apparatus shown in Fig. 3 is particularly applicable for railway traffic controlling systems comprising cab signals controlled by three "proceed" codes and without wayside signals, but is not limited to such systems.

I will next refer to Fig. 4. Here, a block between signals S^3 and S^4 is divided at point i into two sections $h-i$ and $i-j$, and approach relay P adjacent signal S^4 is controlled by contact 29 of relay R^7 , and approach relay P^1 adjacent point i is controlled by a back contact 29 of relay R^6 . Alternators A are controlled and transformers T are energized as in Fig. 3. Coders D^1 and D^2 adjacent signal S^4 are controlled as in Fig. 2 and may operate at the same frequencies respectively, as in Fig. 2. The circuit for primary 9 of transformer t when relay R^8 is de-energized is the same as shown in Fig. 2 when relay R^4 is de-energized. The circuit for primary 9 of transformer t when relay R^8 is energized, however, includes, in addition to the corresponding circuit shown in Fig. 2, a contact 47 which is operated by signal S^4 and which is closed when the arm of signal S^4 occupies its caution or proceed or any intermediate position. The relay W adjacent point i is controlled by a pole-changer 7 operated by signal S^4 , and by contact 41 of relay R^7 . When the arm of signal S^4 occupies the caution or proceed or any intermediate position, pole-changer 7 continues in the position shown in the drawings, but when the arm of signal S^4 goes lower than the caution position, pole-changer 7 is reversed and hence current of reverse polarity is supplied to relay W . The circuit as shown for relay W passes from battery Q^1 , through pole-changer 7, contact 41 of relay R^7 , winding of relay W , and pole-changer 7 back to battery Q^1 . Coders D^4 and D^5 are controlled by relay W as well as by relay P^1 , and may be designed to operate at frequencies of 80 and 180 times per minute, respectively.

If a train enters section $h-i$, relay P^1 becomes energized by its circuit passing from battery Q^2 , through contact 29 of relay R^6 , and the winding of relay P^1 back to battery Q^2 . Alternator A adjacent point i is then operated, and transformer T adjacent point i is then energized, as in Fig. 3. Coder D^5 is then operated by its circuit passing from battery Q^2 , through contact 26 of relay P^1 ,

contacts 45 and 46^a of relay W , contact 23 of coder D^5 , and the winding 24 of coder D^5 back to battery Q^2 . The circuit for primary 10 of a transformer t^c is therefore periodically closed and opened passing from secondary 12 of transformer T , through contact 20 of coder D^5 contacts 43^a and 44 of relay W , and winding 10 of transformer t^c back to secondary 12 of transformer T . Transformer t^c therefore supplies section $h-i$ with alternating current which is periodically interrupted at a frequency which corresponds with that of coder D^5 . When the train enters section $i-j$, de-energizing relay R^7 , and in turn relay W , the circuit for primary 10 of transformer t^c is opened at contact 44 of relay W , and hence transformer t^c is de-energized and supplies no current to section $h-i$.

When the train has moved out of section $i-j$ and occupies section $j-k$, and when a second train occupies section $h-i$, relay W is energized in the reverse direction since pole-changer 7 of signal S^4 is in the reverse position because the arm of signal S^4 is in the stop position. Coder D^4 is therefore energized by its circuit passing from battery Q^2 , through contact 26 of relay P^1 , contacts 45 and 46^b of relay W , contact 23 of coder D^4 , and winding 24 of coder D^4 back to battery Q^2 . Contact 20 of coder D^4 now periodically closes and opens a second circuit for primary winding 10 of transformer t^c passing from secondary winding 12 of transformer T , through contact 20 of coder D^4 , contacts 43^b and 44 of relay W , and winding 10 of transformer t^c back to secondary 12. Transformer t^c therefore supplies section $h-i$ with alternating current which is periodically interrupted at a frequency corresponding with that of coder D^4 .

Fig. 4 also embodies the feature of my invention which, as I have described in connection with Fig. 1, requires only a small number of control contacts in the operating circuits for alternators A and primary 13 of each of the transformers T .

Referring to Fig. 5, the apparatus here shown is similar to that of Fig. 4 except that instead of providing a polarized line relay W , a polarized track relay R^9 is substituted for neutral track relay R^7 . The polarized control of relay R^9 is effected by pole-changer 7 of signal S^4 which is here inserted between track battery 3 and the rails of section $i-j$.

Although I have herein shown and described only a few forms of railway traffic controlling apparatus embodying my invention, it is understood that various changes and modifications may be made therein within the scope of the appended claims without departing from the spirit and scope of my invention.

Having thus described my invention, what I claim is:

1. In combination, a conductor, a source of direct current, a winding in which current is induced by current generated by said source, a transformer the secondary winding of which is connected with said conductor, a circuit including said first winding and the primary winding of said transformer, and means for periodically interrupting said circuit. 5 70
2. In combination, a conductor, a source of direct current, a winding in which current is induced by current controlled by said source, a transformer the secondary winding of which is associated with said conductor, a circuit including said first winding and the primary winding of said transformer, and means for periodically interrupting said circuit. 10 75
3. In combination, a conductor, a source of direct current, a winding in which current is induced by current controlled by said source, a transformer the secondary winding which is associated with said conductor, a circuit including said first winding and the primary winding of said transformer, and means for at times opening said circuit. 15 80
4. In combination, a conductor, a source of direct current, a winding in which current is induced by current controlled by said source, a transformer the secondary winding of which is associated with said conductor, a circuit including said first winding and the primary winding of said transformer, and means for controlling said circuit. 20 85
5. In combination, a conductor, a source of direct current, a winding in which current is induced by current controlled by said source, a circuit including said winding, a plurality of periodically operating contacts, 25 means for selectively including one or another of said contacts in said circuit, and means controlled by said circuit for supplying current to said conductor. 30 90
6. In combination, a conductor, a stretch 35 of railway track, a source of direct current, a winding in which current is induced by current controlled by said source, a circuit including said winding, means for periodically interrupting said circuit, means for controlling said circuit by traffic conditions within said stretch, and means controlled by said circuit for supplying current to said conductor. 40 95
7. In combination, a stretch of railway 45 track over which traffic moves in a given direction, a source of direct current, a winding in which current is induced by current controlled by said source, a circuit including said winding, means for periodically interrupting said circuit, means for controlling said circuit by traffic conditions within a forward section of said stretch, and means controlled by said circuit for supplying current to a rear section of said stretch. 50 100
8. In combination, a first and a second sec- 55 105
- tion of railway track, a source of direct current, a winding in which current is induced by current controlled by said source, a circuit including said winding, means for periodically interrupting said circuit, means for controlling said circuit by traffic conditions in said first section, and means controlled by said circuit for supplying current to said second section. 60 110
9. In combination, a stretch of railway 65 track, a trackway circuit, a source of direct current, a conductor in which current is induced by current controlled by said source, a control circuit including said conductor, means for periodically interrupting said control circuit, means for controlling said control circuit by traffic conditions in said stretch, and means controlled by said control circuit for supplying current to said trackway circuit. 70 115
10. In combination, a stretch of railway 75 track, a source of direct current, a winding in which current is induced by current generated by said source, a track transformer the secondary winding of which is connected across the rails of said stretch, a circuit including said first winding and the primary winding of said track transformer, and means for periodically interrupting said circuit. 80 120
11. In a railway traffic controlling system, a trackway circuit, a source of direct current, a winding, means for supplying said winding with alternating current derived from said source, a transformer the secondary winding of which is connected in said trackway circuit, a control circuit including said first winding and the primary winding of said transformer, and means for periodically interrupting said control circuit. 85 125
12. In a railway traffic controlling system, a trackway circuit, a source of direct current, a transformer the primary winding of which is energized by said source, a second transformer the secondary winding of which is included in said trackway circuit, a control circuit including the secondary winding of said first transformer and the primary winding of said second transformer, and means for periodically interrupting said control circuit. 90 130
13. In a railway traffic controlling system, a trackway circuit, a source of direct current, a transformer, means controlled by said source for alternately energizing the primary of said transformer in opposite directions, a control circuit controlled by said transformer, means for periodically interrupting said control circuit, and means controlled by said control circuit for supplying energy to said trackway circuit. 95 135
14. In combination, a trackway circuit, a transformer having its secondary connected with said circuit, a source of direct current, a second transformer, means receiving ener- 100 140

- gy from said source for periodically energizing the primary of said second transformer, a control circuit including the primary of said first transformer and the secondary of said second transformer, and means for periodically interrupting said control circuit.
- 5 15. In combination, a trackway conductor, a source of direct current, a device operated by current from said source, a transformer, a circuit including the secondary of said transformer, means controlled by said device for so transmitting energy from said source to the primary winding of said transformer that alternating current is generated in the 10 secondary of said transformer, means for periodically interrupting said circuit, and means including said circuit for supplying energy to said conductor.
- 15 16. In combination, a trackway conductor, a source of direct current, a contact which is 20 caused to vibrate by energy from said source, a second conductor, a circuit including said second conductor, means controlled by said contact for causing energy from said source to generate alternating current in said second conductor, means for periodically interrupting said circuit, and means including said circuit for energizing said trackway conductor.
- 25 17. In combination, a stretch of railway 30 track, a trackway conductor, a source of direct current, a second conductor, means controlled by energy periodically supplied by said source for generating alternating current in said second conductor according to 35 traffic conditions in said stretch, a circuit including said second conductor, means for periodically interrupting said circuit, and means including said circuit for energizing said trackway conductor.
- 40 18. In combination, a trackway conductor, a direct current source for supplying energy to said conductor when said stretch is occupied, and means for interrupting such supply of energy when said conductor has 45 been energized a measured period of time.
19. In combination, a trackway conductor, a direct current source, means receiving energy from said source for at times supplying alternating current to said conductor, and 50 means for interrupting such supply of alternating current after the lapse of a measured interval of time.
20. In combination, a section of railway 55 track, means for supplying train controlling current to said section when a train enters the section, and means for discontinuing the supply of said current to said section after the section has been occupied for a given interval of time.
- 59 21. In testimony whereof I affix my signature.
RONALD A. McCANN.
